BY James P. Burns

ATTORNEY.

UNITED STATES PATENT OFFICE

CLARA C. HARRIS, OF SABINA, OHIO

TALLY

Application filed April 13, 1928. Serial No. 269,741.

This invention relates to tallies, to be used during the playing of any kind of game that may be conducted in a progressive manner, and for the purpose of guiding the progress 5 of the entire series of games to be played at a tournament or affair.

The primary object of the invention is to provide a tally which is suitable for a tournament involving a certain number of tables 10 around which, as in auction bridge, a definite number of players are to be positioned.

Another object of the invention is the provision of tallies which may be arranged in combined sets each of which is suitable for a 15 tournament involving either of two different number of tables.

A further object of the invention is the provision of tallies each of which has displayed thereupon a plurality of identifying 20 and designating symbols, characters, names, or signs properly arranged and grouped to provide quickly and easily understood instructions suitable for guiding the progress of a participant through the entire series of 25 games to be played.

A still further object of the invention is to provide tallies of a proper number to supply 30 each person participating with one of the same, every person being guided by his tally so that he will play but one game with each of the other persons participating and will not remain at a table for more than one successive game, thereby permitting every person to reach every table once during the play.

Other objects and advantages of the invention will be apparent during the course of the following description:

In the accompanying drawing forming a 40 part of this specification and in which like numerals are employed to designate like parts throughout the same,

Figure 1 is a front elevational view of one 45 of a set of tallies embodying this invention,

Figures 2 and 3 are front elevational views 50 of a modified form of tally embodying the invention, portions of the said tally being arranged differently with respect to each other in each of the said views, and

Figures 4 and 5 are top edge views of the

tallies illustrated in Figures 2 and 3 respectively.

In the drawing, wherein for the purpose of illustration are shown preferred embodiments of this invention, the numeral 15, in 55 Fig. 1, is employed to designate in its entirety one tally of what will be termed a "single" set of tallies. This tally consists of a card which may be folded if desired along the line 16 to form the portions 15^a 60 and 15^b. The portion 15^a has displayed thereon a series of lines 17 which are designated by the different identification characters 18. These lines 17 are intended to receive the scores made during the different 65 games of a tournament, there being preferably ten games played during the tournament and the games are identified one from the other by the characters 18. The portion 15^a further is provided with a tally identification character 19 which is assumed by the holder of the tally to distinguish him from other participants. Suitable lines 20 may be provided on the portion 15^a for receiving the name of the holder of the tally 70 and any other information desired.

The remaining portion 15^b of the tally has arranged thereupon, in any desired manner or order, a series or group of similarly and characteristically defined or outlined 75 spaces 21. In this particular showing of applicant's invention, the spaces are outlined by triangles. Each triangle may be divided into two parts by a line 22. In one of these parts, each space is provided with a character 23 which is similar to one of the characters 18 employed for identifying the score receiving lines 17. The identification character 23 appearing in a space 21 therefore discloses that this space relates to or is in 80 some way dependent upon the score line 17 bearing the same identification character. The same portion of a space 21 which bears the character 23 also bears table designating 85 indicia 24. In the remaining portion of a space 21, instructions are displayed suitable for guiding the holder of a particular card to a particular partner for the particular game designated in the space, such instruction being designated by the reference character 25. 90

In playing games, such as auction bridge, in a progressive manner, it is usually customary for the hostess to provide each participant with a tally or score and guide card so that the various guests will be properly scattered or distributed at the various tables and with the various players throughout the entire tournament or affair. To add to the pleasure of the game, as well as to arrive at a fair total of score for each participant, it is very desirable to progressively guide the various players during the tournament so that each person will not play as a partner with any other player more than one game during the affair and so that each person will not remain at a table for more than one successive game, thereby permitting every person to reach every table at least once.

With these ideas in mind, it is necessary for each participant to be provided with a tally which will identify the holder from the remaining participants and which will guide the said holder to the proper tables and partners during the affair. For a tournament involving six tables at which auction bridge is to be played, it is necessary to provide twenty-four tallies which will bear the identification characters 1 to 24 respectively. The tally displayed in Fig. 1 bears the identification character 11 and is designated by the numeral 19. This particular tally, therefore, is held by a player who will be identified as number 11 during the entire tournament. The holder of this card 11, prior to the start of the first game which is designated by the character (A), will glance at the spaces designated by the reference character 21 until he finds the space bearing the identification character A. He will be advised by the instructions appearing in this space that he is to play game (A) at table 3 with the party holding tally number 6 as his partner. The holder of tally number 11 will proceed in the same manner to determine the table at which he will play each of the successive games B, C, and D, etc. and with whom he will play these games as a partner.

It is to be understood that this tally number 11 prepared for a six-table tournament merely illustrates one embodiment of applicant's invention and it is to be understood that by providing a different number of tallies and by displaying in the spaces 21 suitable instructions, sets of tallies may be produced for tournaments involving any number of tables.

It often happens that a hostess in preparing for a party will invite a proper number of guests to make up a tournament involving a definite number of tables, for instance, eight tables. Such a hostess, therefore, would procure a set of tallies which would contain thirty-two individual cards. If, however, some of her guests were unable to attend the

party and she were only able to make up seven tables, her set of tallies prepared for eight tables would be inadequate to take care of her guests. For the purpose of overcoming this disadvantage, applicant has devised what will be termed a combined set of tallies which will be suitable for use as a tournament involving either of two different number of tables.

In Figs. 2 to 5, inclusive, there is illustrated a tally designated by the reference character 26 which happens to be tally number 10 of a combined set suitable for a tournament involving either eight or seven tables. In Figs. 2 and 4, the tally is arranged so that its portions 26^a and 26^b are jointly visible. A portion 26^c is folded upon the line 27 so that it will lie against the rear face of the portion 26^b. To retain the portion 26^c in this folded position, the portion 26^b has stamped or struck therefrom a tongue 28 under which the free edge of the portion 26^c is tucked or positioned.

In Figs. 3 and 5, the portion 26^c is folded on the line 27 so that it overlies the front face of the portion 26^b. The tongue 28 is again brought into use to retain the portion 26^c in this selected position.

The front face of the portion 26^a has depicted thereupon the same information as is displayed upon the portion 15^a of the tally shown in Fig. 1; namely, the tally identification character 19, the score receiving lines 17, the line identifying characters 18 and the information receiving lines 20. It is believed unnecessary to devote any further time to description of these features of the tally. In Figs. 2 and 4, the front face of the tally portion 26^b is displayed and this face bears a series of characteristically and similarly defined or outlined spaces 21^a. The characterizing or defining line is in the form of a circle. These spaces 21^a are identified one from the other by characters 23^a which are similar to the characters 18 employed for identifying the various score receiving lines 17. As described in connection with the tally 15 illustrated in Fig. 1, these identification characters 23^a associate the various spaces 21^a with the various score receiving lines 17. As in each of the spaces 21 of the tally illustrated in Fig. 1, the spaces 21^a are each divided into two portions by a line 22^a. One of the portions bears table designating instructions 24^a and a partner identifying instruction 25^a.

In Figs. 3 and 5, the portion 26^c of the tally is displayed with the portion 26^a, the portion 26^b being covered up or concealed by the overlying portion 26^c. The disclosed face of the portion 26^c has displayed thereon game, table, and partner designating instructions which appear in the series of characteristically or similarly defined or outlined spaces 21^a. These instructions, however, differ from

the instructions appearing in the similar game identified spaces on the portion 26^b and are suitable for guiding the holder of the tally through the successive games of a tournament involving a different number of tables than the number of tables taken care of by the instructions appearing on the portion 26^b.

It so happens that the tally illustrated in Figs. 2 to 5, inclusive, bears the identification number 10 and is one of a combined set of tallies suitable for a tournament involving either seven or eight tables. It is to be understood, however, that by merely changing the instructions appearing in the spaces 21^a, the depicted tally may be used as one of a combined set of tallies capable of being used in a tournament involving either of any two different number of tables.

It will be noted that the spaces 21 in the tally illustrated in Fig. 1 are defined or outlined by triangles and that the spaces 21^a appearing on the portions of the tally shown in Figs. 2 to 5, inclusive, are outlined or defined by circles. It also will be noted that the triangular spaces in Fig. 1 are staggered with respect to each other and that the circularly defined spaces in Figs. 2 and 3 are arranged in orderly columns. These variations in shape and arrangement are intended to show that I do not desire to be limited to any particular outline or arrangement as many variations in this respect may be carried out without departing from the spirit of the invention. I also wish to note that I do not desire to be limited to any particular manner in which the instructions are displayed in the outlined or defined spaces. The arrangement shown in the figures merely is intended to illustrate what has been found to be very satisfactory. Should it be found desirable to prepare a set of tallies which would be suitable for use in a tournament involving any one of three different numbers of tables, it merely would be necessary to add one more portion such as those designated by the characters 26^b and 26^c. It is believed that such a modification or change would fall within the spirit of the invention illustrated in Figs. 2 to 5, inclusive, and no further illustration need be provided to show the concept of such a variation.

Having thus described the invention, I claim:

1. A tally for games played progressively at a tournament involving either of two different number of tables, said tally being formed of a plurality of foldably connected sections, one of said sections having printed on one face thereof a score field, the two remaining sections each having printed on one of its faces a series of guiding instructions, one of the two remaining sections having its series of guiding instructions displayed on the face thereof opposite to the display face

of the other remaining section so that the first mentioned remaining section may be folded against the back face or against the front face of the second mentioned remaining section to leave exposed only one of the series of guiding instructions and to conceal the other series and means for holding the first mentioned remaining section in either of its operative positions.

2. A tally card for games played progressively at a tournament involving one of several different number of tables, said tally comprising a multi-part card the said parts bearing printed matter representing respectively a score field and groups of instructions differing one from the other, the groups of instructions being arranged on pivotally connected parts of the tally and movable into superimposed relation with respect to each other so that only one of said groups of instructions will be visible with the score field, and means for securing the parts in superimposed relation.

3. A tally card comprising a plurality of similarly shaped, foldably connected parts, and means carried by one of said parts for engaging an edge of an adjacent part for holding the last mentioned part folded against either the front or rear face of the first mentioned part, the two parts held together by said means being free to move as a unit with respect to the remaining part while the card is in use.

4. A tally card comprising a plurality of similarly shaped, foldably connected parts, and a hinged tab located substantially at the fold line between two of said parts for holding a third part folded against either of the faces of one of the said two parts, the parts held together by said tab being free to move as a unit with respect to the remaining part when the card is in use.
